US00D936526S

(12) **United States Design Patent** (10) **Patent No.:** **US D936,526 S**
Oyanagi et al. (45) **Date of Patent:** **** Nov. 23, 2021**

(54) **MOTORCYCLE**

(71) Applicant: **Kawasaki Jukogyo Kabushiki Kaisha, Kobe (JP)**
(72) Inventors: **Juichi Oyanagi, Kobe (JP); Takumi Uemoto, Kobe (JP); Kaoru Kouchi, Kakogawa (JP)**

(73) Assignee: **KAWASAKI JUKOGYO KABUSHIKI KAISHA**

(**) Term: **15 Years**

(21) Appl. No.: **29/748,921**

(22) Filed: **Sep. 1, 2020**

(51) **LOC (13) Cl.** **12-11**

(52) **U.S. Cl.** **USPC D12/110**
